UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

APPARATUS FOR SUPPLYING POLISHING MATERIAL TO A SERIES OF POLISHING MACHINES.

Application filed November 25, 1925. Serial No. 71,374.

The invention relates to apparatus for supplying polishing material to a series of polishing machines. The apparatus is designed principally for use in polishing 5 plates of glass by the use of a mixture of rouge and water, but is capable of use upon plates of material other than glass, and with polishing powders other than rouge. The invention has for its principal objects; 10 (1) the provision of an improved arrangement for maintaining the rouge or other polishing powder always in suspension in the system including the conduits and fittings employed, so that clogging is prevented; (2) the provision of an arrangement whereby the same character of mixture is supplied to all the machines and maintained constantly uniform; and (3) the provision of an arrangement in which the 15 polishing material is applied in such manner as to give a maximum speed of polishing combined with an economical use of polishing material. Certain embodiments of the invention are illustrated in the accompanying drawings, wherein:

Figure 1 is a side elevation showing in diagrammatic form a simple embodiment of the invention. Fig. 2 is an enlarged detail sectional view. Fig. 3 is an enlarged fragmentary detail view. Fig. 4 is a detail sectional view through a modification. And Fig. 5 is a diagrammatic side elevation view of a modification of the general arrangement shown in Fig. 1.

Referring to Fig. 1, the reference numerals 1, 2, 3, 4, etc. indicate a series of surfacing cars or tables mounted upon a track 5 and arranged in a continuous train so that they may be carried beneath the series of polishing runners 6, 7, 8, 9, etc., such runners being driven by a suitable means, not shown. The mixture of polishing material, such as rouge and water, is supplied from a distributing tank 10 located at a level above the surfacing tables, such tank being provided with a suitable agitator 11 driven from the motor 12 through the intermediary of suitable reducing gearing in the casing 13 and the sprocket drive 14 and 45 bevel gears 15. The mixture is conducted from the distributing tank through a main conduit 16 from which lead the branch conduits 17, 18, 19, 20, etc. which discharge at their lower ends to the various polishing

runners. The supply of rouge mixture for 55 the distributing tank 10 comes from the rouge house 21 in which are located a series of mixers 22, 23, and 24. The mixers are provided with agitating devices similar to the agitating device 11 operated from suitable driving mechanism, not shown, and the mixture is conducted from the tank 24 to the tank 10 by means of the conduit 25 through which the mixture is forced by 60 means of a suitable pump 26 driven from the motor 27. An excess of polishing mixture is supplied through the trough 16 and this excess discharged into a collecting tank 28 located at the right hand end of the trough. The mixture in the collecting tank 70 accumulates until the level of the mixture rises above a predetermined point at which time the motor 29 is automatically started and operates the pump 30 to carry the mixture through the pipe 31 back to the mixer 75 22. The unused mixture is thus returned to the rouge house and mixed in the tank 22 with a fresh supply of rouge and water and then circulated through the mixer 23 to the mixer 24 thus completing the cycle. 80

The apparatus for controlling the flow of rouge mixture from the trough 16 to the troughs 17, 18, 19 and 20 is shown in Fig. 2. A valve seat 32 is provided in the bottom of the trough 16, and the opening through this seat is controlled from the valve 33 mounted upon the stem 33a. This valve is normally pressed down by means of the spring 34 whose tension may be adjusted by 90 means of a bolt 35 threaded through the bracket 36. The stem is provided with a transverse pin 37 lying beneath the lower end of the spring and supported by the forked end of the operating lever 38 fulcrumed on the bracket at 39. The right hand end of this lever which is made of soft iron lies in opposition to the pole piece of an electro-magnet 40, the arrangement being such that when the winding is energized, the valve 32 is opened and when the current through the winding is cut off, the valve is closed by the spring 34. The wires 41 and 42 for supplying the current to the winding lead to a suitable relay device in the casing 43 (Fig. 1), and this relay device is operated from 100 the motor circuit of the motor which drives the runner 6. The relay is so arranged that when the drag of the runner upon the glass

2
or other material being polished rises above a predetermined point, the magnet 40 operates to open the valve 32, thus permitting a flow of rouge from the trough 16 to the trough 17 and thence to the runner 6, or to a point just in advance of such runner. This fresh supply of polishing material acting as a lubricant between the material polished and the runner reduces the drag of the runner, and when this is sufficiently reduced, the current to the magnet 40 is cut off so that the valve 32 closes. The automatic mechanism whereby this is accomplished including the relay means in the casing 43 constitutes no part of the present invention, but is shown and claimed in my copending application, Serial Number 72,963, of even date herewith. It will be understood that the supply of rouge through each of the other branch pipes 18, 19, 20, etc. is similarly controlled, or may be so controlled, if desired, since an automatic control does not constitute a necessary part of the apparatus. As illustrative of this point, Fig. 4 shows a hand controlled valve 44 which may be adjusted by means of the wheel 45 and which controls the flow of polishing mixture from the main conduit 16 to the branch conduit 17. This valve may be adjusted so that a continuous flow of small volume occurs from the trough 16 to the trough 17.

The automatic return of the mixture collected in the tank 28 back to the tank 22 is preferably controlled by means of the float 46 provided with a hollow stem 47 guided for free vertical movement through suitable bearings in the top of the tank. This stem is provided with a slot 48 through which extends a pin 49 (Fig. 3) mounted in the end 40 of a switch lever 50. This lever operates a limit switch in the casing 51 and the actuation of this switch controls the operation of the motor 29. When the level of the liquid in the tank rises above a predetermined point, the lower end of the slot 48 engages the pin 49 and swings the switch lever 50 so that the motor 29 is thrown into operation and continues to operate until the float moves down so that the upper end of the slot 48 again engages the pin 49 and swings the switch in the reverse direction, thus stopping the operation of the motor.

The use of the troughs, which are open at their upper sides, involves an advantage 55 over the use of pipes, in that the danger of clogging the pipes due to the settling of the rouge is reduced and the labor of cleaning the conduits is reduced to a minimum, as all that is necessary is for the operator to move 60 along the troughs loosening any precipitated rouge with a suitable rod dragged along the bottom of the trough. The operation of the conduit system also has the advantage of being open to observation, so that 65 conditions of flow may be corrected promptly.

ly and before the polishing operation is interfered with incident to irregularities which may arise. Other advantages incident to the system will be readily apparent to those skilled in the art.

70 Fig. 5 illustrates a modification involving a somewhat more involved application of the system disclosed in Fig. 1 in its simplest form. In this arrangement, two sets of polishing runners are shown. The set at the 75 right and the apparatus for feeding such runners is the same as heretofore described in connection with Fig. 1 and the parts bear the same reference numerals as in Fig. 1. The collecting tank 10, however, is supplied 80 from a pipe 52 instead of being supplied directly from the pump 26 through the pipe 25 as is the case in the Fig. 1 arrangement. The arrangement for supplying the left hand set of runners 53, 54, 55 and 56 with 85 rouge is substantially the same as that employed for supplying the runners 6, 7, 8, and 9 as heretofore described. The mixture from the tank 24 in the rouge house is carried to the collecting tank 57 by means of the 90 pipe 58 supplied by the pump 26. The mixture is stirred in this tank by means of the agitator 59 operated from the motor 60 in the same manner as described in connection with the tank 10, and flows from the bottom 95 of the tank through the main conduit 61. From this tank the mixture is supplied to the polishing machine through the branch conduits 62, 63, 64, 65, etc., the method of 100 controlling the flow being the same as that heretofore described in connection with Figs. 1 and 2. The excess rouge mixture which is not supplied to the branch conduits flows into a collecting tank 66 corresponding to the tank 28 of Fig. 1. From this tank, the mixture is pumped from time to time through the pipe 52 and into the tank 10, this being accomplished by means of the electric motor 67 which drives the pump 68. The tank is provided with a float 69 which controls a 105 limit switch 71, the construction and operation being the same as heretofore described in connection with the float 46 and switch 51 of the Fig. 1 construction. It will be seen 110 that the system in substance, constitutes a duplication of the arrangement of Fig. 1 with the two sets of apparatus arranged in series, so that only the pair of pipes 31 and 115 58 leading to and from the batch house are required, instead of a multiplicity of such pipes such as would be called for in case the supply of rouge to each set of polishing runners were made independent. This is a practical consideration when the rouge house happens to be located at a considerable distance from the polishing apparatus.

120 What I claim is:

1. The combination with a plurality of 125 polishing machines arranged in series, and means for carrying a series of plates of mate- 130

rial to be polished therebeneath, of a distributing tank for the mixture of liquid and polishing material to be used, means for agitating the contents of such tank, a main conduit extending along the series of machines, a branch conduit extending from said main conduit to each machine, a collecting tank at the end of said main conduit for receiving the excess of mixture flowing through said main conduit and not diverted through the branch conduits, and means for returning the mixture from the collecting tank to the distributing tank, the said collecting tank being located at a level below that of the distributing tank so that a gravity flow is provided between the two tanks through said main conduit, and such main conduit and branch conduits being in the form of troughs having their upper sides open.

5 2. The combination with a plurality of polishing machines arranged in series, and means for carrying a series of plates of material to be polished therebeneath, of a distributing tank for the mixture of liquid and polishing material to be used, means for 10 agitating the contents of such tank, a main conduit extending along the series of machines, a branch conduit extending from said main conduit to each machine, a collecting tank at the end of said main conduit for receiving the excess of mixture flowing through said main conduit and not diverted through the branch conduits, and means for returning the mixture from the collecting tank to the distributing tank, the said collecting tank being located at a level below that of the distributing tank so that a gravity flow is provided between the two tanks through said main conduit.

15 3. The combination with a plurality of polishing machines arranged in series, and means for carrying a series of plates of material to be polished therebeneath, of a distributing tank for the mixture of liquid and polishing material to be used, means for 20 agitating the contents of such tank, a main conduit extending along the series of machines, a branch conduit extending from the main conduit to each machine, a collecting tank at the end of the main conduit for receiving the excess of the mixture flowing through said main conduit and not diverted through the branch conduits, a pump and conduit 25 means for returning the mixture in the collecting tank to the distributing tank, and automatic means for starting the operation of the pump when the level of the mixture in the collecting tank rises above a predetermined point.

30 In testimony whereof, I have hereunto subscribed my name this 23rd day of November, 1925.

HALBERT K. HITCHCOCK.
